UNITED STATES PATENT OFFICE.

CHARLES F. HUMPHREYS, OF LANCASTER, PENNSYLVANIA, ASSIGNOR TO ARMSTRONG CORK COMPANY, OF PITTSBURGH, PENNSYLVANIA, A CORPORATION OF PENNSYLVANIA.

DESIGN FOR A RUG OR SIMILAR ARTICLE.

Application filed April 28, 1926. Serial No. 17,498. Term of patent 7 years.

To all whom it may concern:

Be it known that I, CHARLES F. HUMPHREYS, a citizen of the United States, residing at Lancaster, county of Lancaster, and State of Pennsylvania, have invented a new, original, and ornamental Design for a Rug or Similar Article, of which the following is a specification, reference being had to the accompanying drawing, forming part hereof.

The figure is a plan view of a portion of a rug or similar article, showing my design, it being understood that the design in the representative illustration is repeated throughout the extent of the rug.

The design is preferably executed in various shades or colors, although the particular shadings employed in the illustration are not intended to indicate any particular colors.

I claim:

The ornamental design for a rug or similar article, substantially as shown and described.

In testimony whereof I have hereunto set my hand.

CHARLES F. HUMPHREYS.
